UNITED STATES PATENT OFFICE.

HENRY W. HUBERS, OF DAVENPORT, IOWA.

AUTOMATIC CONTROL DEVICE FOR WASHING MACHINES.

Application filed October 23, 1920. Serial No. 419,068.

To all whom it may concern:

Be it known that I, HENRY W. HUBERS, a citizen of the United States, residing at Davenport, in the county of Scott and State 5 of Iowa, have invented certain new and useful Improvements in Automatic Control Devices for Washing Machines, of which the following is a specification.

My invention has reference to automatic 10 control devices for washing machines, and is specially designed for use with such machines which are electrically operated, or in which the mechanism is under the control of electric devices. It may be adapted, however, to any power driven machines.

In machines of this class which are in domestic use it is customary to leave the machine in operation with a load of clothes, while other house-work is being attended to, 20 but frequently the machine is forgotten, or no track kept of the length of time in which it is in operation, as a result of which it runs longer than is necessary. This occasions a greater amount of wear upon the clothes, as 25 well as upon the machine parts, and there is a corresponding increase in the amount of the electrical current or other source of energy made use of in operating the machine. The chief purpose of my invention is to provide 30 means whereby the mechanism can be set to operate for a predetermined length of time, and automatically cease to operate at the end of such period.

The particular construction, arrangement, 35 and operation of the parts of my invention will be more fully understood from the following specification, reference being had to the drawings accompanying the same, in which:—

Fig. 1 shows a portion of a washing machine with my invention embodied therein.

Fig. 2 is a fragmentary view of such machine at a right angle with the position shown in Fig. 1.

Fig. 3 is a detached view of the traveler 45 and appurtenant parts.

Fig. 4 is a detail of some of the operative parts of the invention.

1 represents the tub portion of a washing 50 machine, supported by a frame 2, in the bottom of which frame is rotatably supported a drive shaft 3, to which movement is imparted from an electric motor or other source of power. In the upper part of the frame is 55 a bracket 4, on which is pivotally mounted a rack-frame 5, carrying a segment rack 6,

in mesh with a gear-pinion 7 on the end of a shaft 8, by which the agitating devices in the tub are driven. Movement is imparted to the rack 6; to oscillate the same, by means of a pitman 9, having a crank connection with a wheel 10 on the shaft 3. No novelty is claimed herein on the foregoing described mechanism.

Journalized on the frame 2 is a threaded 60 shaft 11, on one end of which is fixed a ratchet-wheel 12, which is adapted to be given a partial rotation by a finger 6^a on the rack 6 in each upward movement of such rack. Spaced outwardly from the tub 1 70 is a plate 13, having an opening 14 in front of the shaft 11, across which opening is supported a rod 15, on which is slidably mounted a traveler 16. Such traveler is projected inwardly into a jaw 17, having a 75 semi-circular opening provided with threads for engagement with the threads on the shaft 11. Pivoted to the traveler 16 is an arm 18, on the inner end of which is a complementary jaw 19, also provided with a 80 threaded opening for engagement with the shaft 11. Such jaws are adapted to be held in such engagement by means of a coiled spring 20 uniting the same. The part 16 is extended outwardly into a handle 21, and the arm 18 is provided with a corresponding handle 22, by means of which the jaws 17 and 19 can be disengaged with the shaft 11, and moved to any desired position 85 thereon.

Projecting upwardly from the jaw 19 is an arm 23, having a bent end which is adapted to contact with the arm 24 of a switch 25, whereby the electric connection used in operating the machine may be broken, 90 interrupting the movement of the machine. The reverse movement of the shaft 11 is prevented by a spring-controlled dog 26, in engagement with the teeth of the ratchet-wheel 12.

The arrangement of the threaded shaft 11 and devices for moving the same is such that the movement of the traveler 16 from one end of the shaft to the other, when the machine is in operation, will require a predetermined length of time, for instance, twenty minutes, which is a little more than an average amount of time for which such machines are usually run. At the end of the period the arm 23 engages the switch arm 110 24, stopping the machine, as before set forth. If it is desired to have the machine operate

for one-half of the time the traveler is set midway the ends of the shaft 11, and so on.

For convenience the plate 13 is provided, at the lower edge of the opening 14, with a scale showing the different lengths of time for which it may be desired to have the machine in movement. If the traveler is set at 5, as shown thereon, the movement will be interrupted at the end of five minutes, and so on. At that end of the shaft 11 which is farthest from the switch is a reduced portion 27, upon which the jaws of the traveler can be positioned when it is desired to run the wringing mechanism, separately from the washing devices. The point for setting it in this position is also indicated on the scale.

What I claim and desire to secure by Letters Patent, is:

20 1. In a washing machine, in combination with the electrically controlled operating mechanism thereof, a threaded shaft rotatably mounted in proximity to said operating mechanism, and provided with a blank portion at one of its ends; a traveler releasably connected with said shaft, so as to be capable of being shifted from one point to another thereon, and adapted to be moved longitudinally thereof upon said shaft being suitably rotated; a switch at the end of movement of said traveler, connected with the electrical devices controlling said operating mechanism, and adapted to be opened by said traveler at the end of its movement; and means 35 for communicating the movement of said operating mechanism to said shaft to impart an intermittent rotation thereto.

2. In a washing machine, in combination with the operating mechanism thereof, a

threaded shaft rotatably mounted in proximity to said operating mechanism, and provided with a blank portion at one of its ends; a traveler releasably connected with said shaft, so as to be capable of being adjusted lengthwise thereof, and adapted to be moved longitudinally thereof upon said shaft being rotated; a switch at the end of the movement of said traveler, adapted to be actuated thereby to interrupt the movement of said operating mechanism; a scale indicating the length of time required for said traveler to move from certain points indicated thereon to the end of its movement; and means for communicating the movement of said operating mechanism to said shaft, to impart an intermittent rotation thereto.

3. A device of the class described, comprising a frame and operating mechanism supported thereon; a threaded shaft mounted in proximity to said operating mechanism, provided with a blank space at one of its ends; a traveler mounted so as to be capable of movement lengthwise of said shaft and provided with pivoted jaws adapted for engagement with said shaft, so as to be moved longitudinally thereof upon said shaft being suitably rotated; a switch at the end of said shaft opposite to the blank space thereon, operatively associated with said operating mechanism, and adapted to be actuated by said traveler at the end of its movement, to stop said operating mechanism; and means for communicating the movement of said operating mechanism to said shaft, to give an intermittent rotation thereto.

In testimony whereof I affix my signature.

HENRY W. HUBERS.
